(57) **CLAIM**

The ornamental design for an exhaust muffler, as shown and described.

DESCRIPTION

FIG. 1 is a top, back and side perspective view of a first embodiment of an exhaust muffler embodying my new design.

FIG. 2 is a bottom, front and side perspective view thereof.

FIG. 3 is a top view thereof, the bottom being a mirror image.

FIG. 4 is a first side view thereof, the second side being a mirror image.

FIG. 5 is a back view thereof.

FIG. 6 is a front view thereof.

FIG. 7 is a top, back and side perspective view of a second embodiment of an exhaust muffler embodying my new design.

FIG. 8 is a bottom, front and side perspective view thereof.

FIG. 9 is a top view thereof, the bottom being a mirror image.

FIG. 10 is a first side view thereof, the second side being a mirror image.

FIG. 11 is a back view thereof; and,

FIG. 12 is a front view thereof.

Broken lines are used to illustrate features of the exhaust muffler which form no part of the claimed design.
